UNITED STATES PATENT OFFICE.

MAX GARBELL, OF CHICAGO, ILLINOIS, ASSIGNOR, BY MESNE ASSIGNMENTS, TO O. D. JENNINGS & COMPANY, OF CHICAGO, ILLINOIS, A CORPORATION OF ILLINOIS.

TYPEWRITING MACHINE.

Application filed April 25, 1921. Serial No. 464,133.

To all whom it may concern:

Be it known that I, MAX GARBELL, a citizen of the United States, residing at Chicago, in the county of Cook and State of Illinois, have invented a certain new and useful Improvement in Typewriting Machines, of which the following is a full, clear, concise, and exact description, reference being had to the accompanying drawings, forming a part of this specification.

This invention relates to improvements in typewriting machines.

The main object of the invention is to provide, in a typewriting machine having a platen carriage arranged to assume different case printing positions, simple, effective, light, and durable means by which the case printing position of the platen is accurately determined and which also are so arranged that they may be adjusted to permit of a ready removal of the platen carriage with its platen and associated parts from the main frame of the machine and the carriage also readily replaced to the end that the typewriting machine may employ interchangeable platens for doing work of different character. The invention is particularly applicable but not necessarily limited to use in connection with a typewriting machine of the character disclosed in my prior Patent 1,305,893, granted June 3, 1919. The invention, while primarily adapted to a typewriting machine of the portable type as disclosed in my said prior patent, is of equal advantage in heavier machines of the so-called non-portable type.

More specifically, an object of my invention is to provide, in a typewriting machine having a platen mounted on a carriage so that the platen is shiftable longitudinally in the usual manner and the platen and carriage vertically shiftable for different case printing positions, key-operated case-shifting means associated with the carriage to elevate it from the normal printing position to one or more higher printing positions, said key-operated case shifting means being disconnected from the carriage when desired to enable the carriage being withdrawn from the main frame of the machine.

A more specific object of the invention is to provide, in a machine having a removable platen and carriage, cooperating case-shift stops on the carriage and main frame for determining the case printing position of the platen in combination with means by which said cooperating stops may be rendered relatively inoperative and so locked automatically when the carriage and its platen are removed, said means being further combined with additional means to release the locking means automatically when the carriage or a substitute carriage is replaced on the main frame.

In the drawings forming a part of this specification, I have shown only such parts of a typewriting machine as are necessary to explain the present invention but reference may be had to my said prior patent and also to my pending application Serial No. 360,598 filed February 24, 1920, for typewriting machines, now Patent No. 1,457,970, for a disclosure of the other parts of a typewriting machine such as my improvements are intended to be associated with.

In said drawings, Figure 1 is a broken, top plan view of the rear portion of a typewriter showing my improvements in connection therewith, the platen, the platen frame and the platen sub-frame being omitted. Figure 2 is a vertical, sectional view corresponding substantially to the section line 2-2 of Figure 1. In both Figures 1 and 2, the condition of the parts is such as obtains when the platen carriage is in position and adapted for case shifting. Figures 3 and 4 are views corresponding respectively with Figures 1 and 2 but showing the condition of certain of the parts preliminary to the removal of the carriage from the main frame. Figure 5 is a vertical, sectional view taken from the front to the rear of the machine and corresponding substantially to the line 5-5 of Figure 1. Figure 6 is a vertical, sectional view corresponding substantially to the section line 6-6 of Figure 1. The dotted lines in Figure 6 indicate the positions of certain of the parts assumed during the replacement of the carriage on the main frame. Figure 7 is a detail, sectional view

corresponding substantially to the section line 7-7 of Figure 5. And Figures 8, 9 and 10, are views corresponding respectively to Figures 1, 2 and 6, but illustrating another embodiment of the invention. In Figures 8 and 9, only the central portions of the machine are shown since the modification is confined to the coupling between the release shafts and the locking mechanism associated 10 with said coupling.

Referring first to the construction illustrated in Figures 1 to 7, inclusive, 20 denotes the main frame of the machine, the same having side walls 21 and 22, a back wall 23, and an upper wall or bridge 24. The main frame is adapted to be supported on suitable cushion pads or feet as indicated at 25. At the back, the main frame is provided, near the opposite sides thereof, with a pair 20 of rigidly secured brackets 26 from each of which extends upwardly a cylindrical post 27 rounded at its upper end as indicated at 27^a. The tops of said posts 27 are terminated above the upper edge of the rear 25 wall 23.

A portion of a platen is indicated at 28 in Figure 5, the same being rotatably mounted on a platen frame or carriage indicated at 29. Said platen frame is provided with 30 horizontally extending guides or tracks 30 and 31 which are disposed opposite corresponding guides or tracks 130 and 131, respectively, carried on a platen sub-frame 32. Anti-friction balls 133 are interposed between 35 the said tracks, which are grooved to receive the same, so that the platen and its frame or carriage are adapted to move cross-wise of the machine step by step in the usual manner to bring different portions of 40 the platen opposite the printing point. In this connection, it will be understood that an escapement mechanism will be employed together with such other details as may be found advisable in a typewriter. The sub-frame 32 is rigidly supported on a pair of 45 triangular stamped metal brackets 33, each of said brackets 33 having curved forked arms 33^a-33^b which are rigidly secured to a cylindrical hollow sleeve 34 which fits 50 smoothly over one of the posts 27. With the arrangement of sleeves and posts described, it is evident that the platen, together with the associated platen frame or carriage and carriage support, composed of 55 the sub-frame 32 and brackets 33, are adapted for vertical movement relatively to the main frame of the machine and are guided in such movements. It will also be observed that the carriage support, carriage and 60 platen may be vertically applied to and vertically removed from the posts 27.

In the arrangement which I have chosen for illustrating my invention, the platen is intended to have three case printing positions, the lowermost position being that il-

lustrated in the drawings, which ordinarily will correspond to the lower case letters of the type bars. The next higher or intermediate position will preferably correspond to the higher case letters or capitals and the 70 third or uppermost printing position of the platen will correspond to the figures and other special characters carried by the type bars. To effect the case shifting of the 75 platen with its associated carriage and carriage support, I employ key levers 35, preferably one on each side of the machine, each of said levers being pivotally mounted on a cross rod as indicated at 36 in Figure 5. At its inner end, each capital shift lever 35 80 is forked so as to provide an upper branch 37 and a lower branch 38. The upper branch 37, as best shown in Figures 1 and 5, is comparatively short and is laterally outwardly offset with respect to the main portion of the lever 35 as indicated at 37^a in Figure 1. The lower branch 38 of each of 85 said levers is preferably continued in the general plane of the main portion to a point flush with the end of the branch 37 and is then extended outwardly at a right angle as indicated at 38^a in Figure 1, for a short distance, and thence parallel to the main portion as indicated at 38^b. The two branches 90 37 and 38 will have a slot 39 therebetween 95 within which slidably engages a laterally extended stud 40 provided on the corresponding adjacent bracket 33. By depressing the outer end of either one of the capital shift keys 35, it is evident that the 100 platen and its carriage will be elevated. To partially compensate for the weight of the platen carriage and carriage support which acts, under gravity, to return the carriage support, carriage and platen and shift keys 105 35 to their normal position shown in Figure 5, a tension spring 41 is employed, one end being attached to the bridge 24, as indicated at 42 and the other end to the lever as 110 indicated at 43.

For shifting the platen and its carriage and carriage support to the uppermost or figure case printing position, I employ figure shift keys 44 extending alongside the corresponding capital shift keys 35 and fulcruming about the same rod 36. Each of the figure shift keys 44 is adapted to be retracted to normal position by a tension spring 45 secured at one end to the bridge 24 and at its other end to the key as best 115 seen in Figure 5. The figure shift keys 44 do not have any direct engagement with the carriage support but elevate the latter through the instrumentality of the capital shift keys 35 and for this purpose, as best 120 shown in Figure 7, each figure shift key 44 has a laterally bent flange 46 extended over the upper edge of the corresponding capital shift key 35 so that, when the figure shift key is depressed, the capital shift key will 125 130

necessarily be depressed simultaneously and uniformly therewith. The means determining the capital or figure case printing positions of the platen carriage and carriage support will next be described.

Extending transversely of the main frame 20 are two alined rock shafts 47 and 48, the same being coupled together so as to rock in unison and also adapted to be moved longitudinally toward and from each other by means which will be described herein-after. Each shaft 47 and 48 is mounted in a suitable bearing provided in the corresponding bracket 26 secured to the back wall of the main frame. Each of said shafts 47 and 48 has rigidly secured thereto adjacent but on the outer side of the corresponding bracket 26, a lever 49. Each of said levers 49 normally extends upwardly in a general vertical direction as best shown in Figure 5 and is provided with a horizontally extending case-shift stop shoulder 50 vertically above the pivotal axis of the lever. The lower outermost arm 33^a of each bracket 33 is formed with a cooperating laterally extended flange 51 forming a cooperating case-shift stop shoulder which is normally spaced below and directly beneath the corresponding shoulder 50, as shown in Figure 5. The levers 49 are each spring-influenced by a coil spring 52 so as to swing in a clockwise direction as viewed in Figure 5, the levers 49 being held by the engagement of an arm 53 at the upper end thereof with the back wall 23 of the main frame.

When either of the capital shift keys 35 is depressed and the carriage support, carriage and platen correspondingly elevated, the levers 49 remain unaffected and hence the upper intermediate position of the carriage support, carriage and platen is determined by the shoulders 51 engaging with the shoulders 50, that is, the intermediate case-shift position.

To permit the carriage support, carriage and platen to be elevated to the uppermost or figure case printing position upon depression of either of the figure shift keys 44, the following arrangement is employed. As shown in Figure 5, the figure shift key 44 is provided with a depending arm 54 to which is pivotally connected one end of a link 55, the opposite end of said link being slidably pivotally connected to the lever 49 by means of an inturned arm 56 engaging in a slightly arcuate slot 57 formed on the lower end of the lever 49. Upon depression of either figure shift key 44 not only will the carriage support, carriage and its platen be elevated through the intermediary of the capital shift key 35, as heretofore explained, but also the levers 49 will be oscillated in a counterclockwise direction through the corresponding link 55 so as to remove the shoulders 50 from the path of the shoulders 51 and thereby

bring into vertical alinement with the shoulders 51, other high cooperating case-shift stop shoulders 58 formed on the under side of said arms 53 of the levers 49. In this connection it will be borne in mind that the two shafts 47 and 48 and consequently the levers 49 are simultaneously rocked by means of the coupling heretofore referred to so that the action is the same on both sides of the machine. By means of the lost motion provided by the slots 57, when the figure shift key on one side of the machine is actuated, the lever 49 on the opposite side is free to operate without affecting the corresponding link 55 on that side of the machine.

In order to permit removal of the platen and its carriage and carriage support from the main frame when desired, it becomes necessary to disconnect the key-operated shift levers from the carriage support and also eliminate any interference with the upward movement of the shoulders 51 rigid with the carriage support. The means for accomplishing the results specified reside principally in the coupling between the two shafts 47 and 48, shown best in Figures 1, 2, 3, 4 and 6.

Rigidly secured to the back wall 23 of the main frame is a plate 59 having forwardly extended arms 60 and 61 which are suitably apertured to provide bearings for the shafts 47 and 48, respectively. From the center of the back portion of the plate 59 is extended forwardly a stud 62 upon which is pivotally mounted to oscillate about a horizontal axis, a lever having an upwardly extending arm 63 and a downwardly extending arm 64. Said lever 63-64 may be held in position by a pivot-forming screw 65.

The shafts 47 and 48, at their adjacent inner ends, are provided each with a collar 66, rigidly secured thereto by a pin or other suitable device. Each of said collars 66 is formed with a sheet metal plate section 67 extending at right angles to the axes of the shafts, said plate section at one of its ends being turned at right angles and formed with a horizontal relatively wide section 68 and with a narrow finger 69 extending therefrom. Each section 68 is provided with a substantially square opening 70. On the opposite side to that of the arm 67, each collar 66 is formed with an oppositely extending arm 71 which is notched at its end as indicated at 72 in Figure 6.

While the collars 66 and parts rigidly associated therewith are preferably of like construction, they are angularly offset 180° with respect to each other so that the two openings 70 are diametrically opposite and the finger 69 of one slidably engages in the notch 72 of the other, as shown in Figures 1, 2 and 6. With this arrangement it will be obvious that the two shafts 47 and 48 are

coupled so as to rotate in unison but are, nevertheless, adapted for relative movement axially toward and from each other. The upper openings 70 loosely receives therein the tapered end of the arm 63 and the lowermost opening 70 receives the corresponding tapered lower end 64 of said lever 63-64. It will be noted that there is sufficient clearance between the sides of the lever arms 63 and 64 and the opposed edges defining the openings 70, as indicated at 73 to permit such rocking movement of the shafts 47 and 48 as may be necessary in the swinging of the case stop shoulder levers 49-49.

One of the shafts, the shaft 47 as shown in the drawings, is extended through a suitable opening in the corresponding side wall 21 of the main frame and provided at its outer end with a hand grip or knob 74 so that the same may be pulled toward the left from normal position, as viewed in Figure 1. To said shaft 47 is also rigidly secured a split collar 75, the same having an annular groove 76 within which extend diametrically opposite pins 77 carried by a U-shaped stamped sheet metal yoke 78 which straddles said collar 75. At its inner end, that is, the end adjacent the back wall 23 of the main frame, the upper and lower arms of said yoke 78 are pivotally connected to upper and lower extensions 79-79 stamped integrally with the plate 59 so that said yoke 78 is fulcrumed at its inner end. With this arrangement it is evident that, upon pulling the shaft 47 outwardly toward the left from its normal position, that is, from the condition shown in Figure 1 to that shown in Figures 3 and 4, the yoke 78 will be oscillated from that position shown in Figure 1 to that shown in Figure 3 and simultaneously the lever 63-64 will be oscillated about a horizontal axis thereby simultaneously pushing the shaft 48 toward the right, as viewed in Figures 1 to 4 inclusive. This simultaneous outward but opposite movement of the shafts 47-48 causes the respective stop shoulder levers 49 to be oppositely outwardly moved and in so doing, said levers 49 engage the respective flanges 38^b of the capital shift levers 35 and spring the same outwardly so that the upper branches 37 of each of said levers 35 is pulled outwardly sufficiently to clear the studs 40. This releases the carriage support from the shift keys, as will be understood. In moving outward oppositely as just described, the levers 49 also pass beyond the vertical paths of the stop shoulders 51-51, as best indicated in Figures 3 and 4 so that no obstruction remains to the vertical removal of the carriage support by reason of said levers 49.

After the parts have been operated to the release condition just described to per-

mit removal of the carriage support, it is desirable that the release condition be maintained automatically until such time as the carriage support is replaced or a different carriage and carriage support substituted. To this end, I provide the following arrangement.

Referring to Figures 1 to 4 inclusive, it will be noted that the arm 61 of the plate 59 is turned at right angles at the outer end so as to provide a vertically extending plate 80 which is parallel to the shaft 48. Said plate 80 is of special form and is provided with a vertically extending elongated slot 81 and with a slot 82 which is inclined 80 slightly from the horizontal downwardly toward the right, as viewed in Figures 2 and 4. Said slot 82 is provided with an offset at its upper lefthand end as indicated at 83 so as to produce a shoulder 84. Loosely 85 pivotally connected to the cross piece of the yoke 78 as by means of a headed pin 85 is an elongated stamped sheet metal lever 86, the same extending parallel to the shafts 47 and 48. Said lever 86, at its free end, 90 is formed with an upward extension 86^a from which in turn is forwardly extended at right angles a flange 86^b notched on its upper and lower edges as indicated at 86^c and riding in said slot 82. A tension spring 87 is connected at one end to a downwardly extending arm 86^d of said lever 86 and at its other end to the stationary arm 61 so that the spring 87 always tends to swing the lever 86 in a counterclockwise direction 100 about its fulcrum or pivot 85. With the arrangement shown, as the shaft 47 is pulled outwardly toward the left and the yoke lever 78 swung about its fulcrum, as hereinbefore described, the lever 86 is compelled 105 to travel toward the left as viewed in Figures 2 and 4 until finally the flange 86^b thereof snaps up into the offset 83 in the slot 82 and engages behind the shoulder 84. This condition is shown in Figures 3 and 110 4 from which it will be observed that the parts are thus automatically held in locked release condition.

It is also desirable that the locking mechanism, just described, be rendered inoperative automatically when the carriage and carriage support are replaced on the main frame so as to insure the re-establishing of the operative connections and positions of the case-shifting means and 115 case-shift stops. To accomplish this result, I employ the following arrangement, particular reference being had to Figures 4 and 6. As hereinbefore mentioned, an escapement mechanism of suitable character will be mounted on the platen carriage support and carriage, said escapement mechanism being operated by a link 88 which has a detachable pivotal connection as indicated at 89 with another op- 120 125 130

erating link 90 which in turn is actuated by one arm of a bell crank lever indicated at 91, the latter in turn being operated by the usual spacer bar of the machine. The link 5 90 has its inner end extended through and working in said slot 81, and the lever 86 is sufficiently downwardly offset where it passes beneath the link 90 so as to always clear the latter and avoid engagement there- 10 with. When the carriage and carriage support are withdrawn from the frame, the escapement operating link 88 is lifted upwardly as indicated by the dotted position of Figure 6 which in turn permits the link 15 90 to be oscillated upwardly within the slot 81, by means of the spring 92. Continued upward movement of the carriage and support beyond the dotted position shown in Figure 6 will, of course, withdraw the pivot 20 89 from the open bearing in the link 90 and leave the latter in its elevated position. When the carriage and support are being replaced, during which time the locking mechanism is of course operative, the es- 25 capement operating link 88 re-engages with the link 90 as indicated by the dotted lines in Figure 6. Continued lowering of the carriage and carriage support causes the link 90 to be depressed until it reaches a 30 position indicated by dotted lines at 90^a in Figure 4 when it then engages the arm 93 of a spring-controlled pawl pivotally mounted on the part 86^a of the lever 86. Said pawl is provided with a shoulder on 35 the opposite side of the pivot as indicated at 94 which engages with the flange 86^b and thereby prevents oscillation of said pawl 93—94 in a counter-clockwise direction about its pivot, as viewed in Figure 4. Conse- 40 quently as the link 90 continues in its downward movement below the dotted position shown at 90^a in Figure 4, not only will the pawl be depressed but it in turn will depress the lever 86 until finally the flange 86^b is 45 disengaged from behind the shoulder 84 and the lever 86 is then released and projected to the right, as viewed in Figure 4, under the influence of the tension spring 87. The locking mechanism is thus released and 50 simultaneously therewith the two shafts 47 and 48 are drawn axially toward each other thus in turn bringing the stop shoulder levers 49 into operative position and the case-shift keys into operative connection 55 with the studs 40 of the carriage support. The pawl 93—94 is free to oscillate against the action of the spring 95 in a clockwise direction, as viewed in Figure 4 so that, when the locking mechanism has been set as 60 shown in Figure 4, the upward movement of the link 90 will easily pass by the arm 93 of the pawl without affecting the locking mechanism.

Referring next to the construction illus- 65 trated in Figures 8 to 10 inclusive, it will be

understood that the key-operated case-shift devices and the case-shift stop shoulders on the frame and carriage support remain the same. The modification shown in Figures 8 to 10 relates to the coupling, locking mech- 70 anism and lock release mechanism. As shown, two shafts 147 and 148 are employed, both mounted and adapted to operate the same as the corresponding shafts 47 and 48 shown in the other figures. Secured to the 75 back wall 123 of the main frame is a stamped sheet metal plate 159 having laterally spaced forwardly extending arms 160 and 161 suitably apertured to provide bearings for the shafts 147 and 148. The shafts 80 147 and 148 are provided with collars 166—166 having parts corresponding to those referenced 67, 68, 69, 70, 71 and 72 of the form shown in Figures 1 to 6 inclusive and which need not here 85 be detailed. A corresponding lever 163—164 is employed cooperable with the 90 slideable coupling as in the case of the first described form.

To lock the shafts 147—148 when the same 90 are spread apart, I employ a slide bar 186 which, at its lefthand end as viewed in Figure 9, is provided with a depending arm 186^a having a collar 100 loosely encircling the shaft 147 and adapted for a slight oscil- 95 lation thereon. Said collar 100 is formed with a rounded knob 101 providing a loose fulcrum on a collar 175 rigidly fastened to the shaft 147. The opposite end of said slide 186 extends through an opening 182 100 formed in the arm 161, the upper portion of the metal defining said opening 182 providing a shoulder 184 with which is adapted to cooperate a shoulder 186^b on the slide 186. A tension spring 187 is connected at one end to said arm 186^a and to a suitable portion of the side of the arm 160 so that said spring always tends to swing the right- 105 hand end of the slide 186 upwardly, as viewed in Figure 9.

When the shaft 147 is pulled to the left, as viewed in Figures 8 and 9, it is evident that the slide 186 will be correspondingly moved and ultimately the shoulder 186^b thereof will be snapped up behind said sta- 110 tionary shoulder 184 and thereby lock the two shafts 147 and 148 in their separated position. To prevent the shafts 147 and 148 from returning accidentally to their nor- 115 mal position without releasing the slide 186 from engagement with the shoulder 184, after the locking mechanism has been set, the slide 186 is provided with a depending finger 186^a that engages the opposite side of the collar 175 to that engaged by the knob 101. 120

To release the locking mechanism just de- 125 scribed, a spring-controlled pawl having an arm 193 is pivotally mounted on the slide 186, said arm 193 remaining in the path of 130

the escapement operating link 190 when the lock mechanism is operated. Said link 190 is vertically slideable within an elongated slot 181 and rises and falls under the said conditions as the link 90. When depressed upon replacement of the carriage, it is evident that said link 190 will engage the arm 193 of the pawl and thereby depress the slide 186 so as to disengage the shoulder 186^b from the shoulder 184 and thereby permit the slide 186 to be projected toward the right under the influence of the spring 187, as viewed in Figure 9 and thus returning all of the parts to normal condition. In this connection, it will be observed that said pawl has a shoulder 194 engageable with a flange 102 on the slide 186 to prevent the pawl from being oscillated in a counter-clockwise direction but without interfering with oscillation in a clockwise direction, as will be understood.

I have herein shown and described what I now consider the preferred manner of carrying out my invention but the drawings and description are by way of illustration only and not by way of limitation, as I am aware that many changes and modifications may be made in the details of construction and arrangement of parts without departing from the spirit of the invention. All changes and modifications are contemplated that come within the scope of the claims appended hereto.

I claim:

1. In a typewriting machine, the combination with a main frame, a platen carriage and carriage support adapted for case-shift movement with respect to said frame, and cooperable disengageable means on said carriage support and frame arranged to guide the carriage support in its case-shifting movements; of case-shifting means cooperable with said carriage support; cooperable case-shift stops mounted on said carriage support and frame; manually operable means for rendering said case-shift stops relatively non-cooperative; locking means cooperable with said manually operable means for automatically maintaining said non-cooperative relation of said case-shift stops; and means, mounted on the carriage support, cooperable with said locking means arranged to release the latter upon replacement of the carriage support on the main frame.

2. In a typewriting machine, the combination with a main frame, a platen carriage support adapted for case-shift movement on the frame, and cooperable but disengageable means on said carriage support and frame arranged to guide the carriage support in its case shift movements; of key-operated case-shift means cooperable with said carriage support; cooperable case-shift stops

mounted on the carriage support and frame; manually operable means for simultaneously rendering said case-shift stops relatively non-cooperative and disconnecting said case-shifting means and the carriage support; locking means cooperable with said manually operable means for automatically maintaining a non-cooperable relation of the case-shift stops and disconnected condition of the case-shifting means; and means, operated by replacement of the carriage support on the main frame, for releasing said locking means.

3. In a typewriting machine, the combination with a main frame having vertically extending carriage support guides thereon; of a platen carriage support having cooperating guiding elements; case-shift stops rigid with and mounted at each end of the carriage support; cooperable movable case-shift stops on said main frame at each end of the carriage support; means for simultaneously moving said movable stops away from and out of operative relation with respect to said case-shift stops on the carriage support to thereby permit removal of the carriage support from the frame; means for automatically locking said movable stops in their said inoperative position; and means, including an element mounted on the carriage support and an element mounted on the main frame, cooperable with said locking means to release the latter upon replacement of the carriage support on the frame.

4. In a typewriting machine, the combination with a main frame having vertically extending carriage support guides thereon; of a platen carriage support having cooperating guiding elements; case-shift stops rigid with and mounted at each end of the carriage support; cooperable movable case-shift stops on said main frame at each end of the carriage support; and means for simultaneously moving said movable stops away from and out of operative relation with respect to said case shift stops on the carriage support to thereby permit removal of the carriage support from the frame, said means including, a pair of slidably mounted rock shafts upon each of which one of said movable stops is carried.

5. In a typewriting machine, the combination with a main frame having vertically extending carriage support guides; of a platen carriage support having cooperable guiding elements; means for imparting a vertical case-shift movement to said carriage support; case-shift stops rigid with and mounted on each end of said carriage support; cooperable movable case-shift stops mounted on said frame at each end of the carriage support; means for simultaneously but oppositely moving said movable stops away from and out of the operative rela-

tion with respect to said stops on the carriage support, said means including, a pair of slidably mounted rock shafts upon each of which a movable stop is carried and a combined coupling and motion-reversing device interposed between adjacent parts of said shafts.

In witness that I claim the foregoing, I have hereunto subscribed my name this 8 day of April, 1921.

MAX GARBELL.
